UNITED STATES PATENT OFFICE.

HARRY C. HORNISH, OF CHICAGO, ILLINOIS, ASSIGNOR TO ALFRED S. CLARK AND CHARLES F. DENNHARDT, OF CHICAGO, ILLINOIS.

VAPOR-BURNER.

SPECIFICATION forming part of Letters Patent No. 792,519, dated June 13, 1905.

Application filed May 15, 1903. Serial No. 157,199.

To all whom it may concern:

Be it known that I, HARRY C. HORNISH, a citizen of the United States, residing at Chicago, in the county of Cook and State of Illinois, have invented certain new and useful Improvements in Vapor-Burners, of which the following is a specification.

My invention relates to vapor-burners; and it consists in the several features of improvement as hereinafter described in connection with the accompanying drawings and more particularly pointed out in the claims.

Referring to the accompanying drawings, which form a part of this specification and in which the same reference characters designate the same parts in all of the views, Figure 1 is a central vertical sectional view of a burner embodying the features of my invention. Fig. 2 is a sectional view on the line 2 2 of Fig. 1 looking in the direction of the arrow. Fig. 3 is a bottom plan view of the base-plate of the burner, showing the cut-off for the mixing-passage in its position when the burner is lighted. Fig. 4 is a view similar to Fig. 3, but showing the cut-off in position when gas is generated to light the burner. Fig. 5 is a detail sectional view of the burner, showing the manner of mounting the cleaning-tubes. Fig. 6 is a broken sectional view on the line 6 6 of Fig. 5 with the vertical cleaning-tube partly removed, the view being taken in the direction of the arrow; and Fig. 7 is an elevation of the longitudinal cleaning-tube.

Referring to the parts by reference characters, the numeral 1 denotes a generating chamber or retort that is substantially annular in outline and is provided with downwardly-projecting tubes 2 and 3, cast integrally therewith at opposite points and with which the oil-supply pipe 4 and the gas-discharge pipe 5, respectively, connect. The oil-supply pipe 4 is connected to the tube 2 in any suitable manner and preferably by means of the T-shaped head 6, having cross-passages connecting, respectively, with the oil-pipe 4 and the tube 2, the passage to the tube 2 being closed at its opposite end by a suitable cap, with which may be associated an

annular washer of asbestos or other suitable material. The gas-discharge pipe 5 leads inwardly to the center of the retort by means of the longitudinal leg or branch 7, which is closed by a suitable plug 8 and is provided with a gas jet or exit 9, which is controlled by an ordinary needle-valve 10.

The tubes 2 and 3 form convenient supports for a base-plate or deflecting-plate 11, which preferably is cast integrally with the tubes by means of suitable connecting-webs 12. The retort is also provided with a pair of downwardly-projecting oppositely-disposed posts 13 and 14, formed integrally with the retort and with the base-plate and arranged intermediate the tubes 2 and 3, as shown in Fig. 2. The plate 11 is provided with a central mixing-passage 15, preferably formed in a slightly-thickened portion of the plate and in line with the gas-exit 9. The plate 11 is provided with a series of curved deflecting-flanges 16, which are vertically disposed and are arranged at or near the edge of the plate and have intermediate openings or passages 17, as shown in Figs. 1 and 2. The deflectors 16 direct the flame upwardly to cause it to impinge on the spreader 18, while the intermediate openings 17 permit portions of the flame to pass laterally beneath the ring 1 and against the tubes 2 and 3 and the posts 13 14 to keep all of these parts properly heated. The deflectors adjacent to the tubes 2 and 3 are provided with beveled or rounded edges or ends in order to insure the direction of the flame against these tubes. The arrangement and disposition of the deflectors are clearly shown in Figs. 1 and 2.

The spreader 18 is in the form of an inverted dish, as shown in Fig. 1, and is provided with any suitable means to seat upon the retort, as legs 19. It is also provided with a plurality of slits or openings 20, which preferably are four in number, arranged at equal distances around its edge or periphery to permit the passage of portions of the flame.

The burner is provided with a cut-off consisting of a plate 21, adapted to slide or reciprocate over the bottom face of the base-

plate 11 in any suitable guides. For this purpose I have provided a pair of downwardly-projecting headed lugs or screws 22, secured in the posts 13 and 14 and adapted 5 to enter elongated slots 23 in the valve or cut-off. The cut-off is provided with lateral lugs or rests 24 to steady it upon the under side of the base-plate and prevent its being displaced. The cut-off is also provided with a 10 central body 25, that is deflected downwardly out of the general horizontal plane of the plate and which is provided with a mixing and guiding tube 26, that is adapted to register with the exit 9 and the passage 15 when 15 the cut-off or valve is at the limit of its movement in one direction, as shown in Figs. 1 and 3. By this construction the upper end of the tube 26 terminates short of the plate 11, so as to provide an air-inlet between the 20 passage and the tube in addition to that at the lower end of the tube, with the result that a more intense blue flame is secured. The body of the cut-off is provided with an auxiliary mixing-tube 27, which is offset lateral 25 to the tube 26, the two tubes being in line across the body and being formed in the body of the slide or cut-off. The tube 27 opens below and in line with the under surface of the plate 21 and is employed when gas is generated 30 to light the burner, at which time the cut-off is shifted to the position of Fig. 4, whereby the portion of the plate above the auxiliary tube 27 forms a closure for the passage 15 and the tube 27 is in alinement with 35 the jet 9. In this position of the slide or cut-off vapor from the jet 9 impinges on the lower surface of the plate 21, and in order to prevent any oil from running off the end of the cut-off I provide the latter with a deflecting-rib 28, which causes any oil that 40 may be deposited on the slide to fall into a suitable drip-pan 29. When gas is generated and it is desired to light the burner, the cut-off is thrown to the position of Figs. 1 and 3 to bring the mixing-tube 26 in register 45 with the jet 9 and passage 15, and the gas and air carry through and mix within the tube 26 and passage 15 to the chamber formed between the base-plate 11 and the 50 cap or spreader 18. It is obvious that the cut-off may be reversed in position, so as to afford either a right or a left hand burner.

The drip-pan 29 is supported in any suitable manner and preferably by means of a vertical and downwardly-projecting leg 30 on the under side of the longitudinal branch 7 of the gas-discharge pipe, through which the valve 10 passes and with which it has threaded connection for adjustment. The leg is 55 exteriorly screw-threaded to receive a suitable screw-nut 31, which holds the drip-pan securely in place, and a stuffing or packing ring 32 for the valve 10.

The bore of the feed-tube 2 and the vertical passage of the head 6 are in alinement

and are adapted to receive a hollow cleaning-tube 33, which fills the passage and extends therein to the retort or generating-chamber, having an opening in register with the supply-pipe 4. The lower end of the head is closed 70 by a cap 35, so that the cleaning-tube 33 may be removed when it is desired to clean the burner, the tube being provided with a hole 36 to receive a suitable pin for withdrawing the same when the cap is removed. The 75 bore of the tube 3 and discharge-pipe 5 are similarly provided with a hollow cleaning-tube 37, which passes through an annular projection on the drip-pan 29 in line with the bore of the pipe 5 and provided with a removable closing-cap 38. The tube 39 has a hole 39 for the same purpose as the hole 35 in the tube 33 and a lateral exit or passage 40 in register with the bore of the branch 7. The bore of the vertical pipe 5 is somewhat less 80 in diameter than that of the longitudinal branch 7, and the latter extends somewhat beyond and outside the pipe 5, where it is closed by a removable cap 41. The bore of the branch 7 is provided with a hollow cleaning-tube 42, removable therefrom when the 85 cap 41 is unscrewed by a pin or other tool engaging the hole 43 therein. The tube 42 is provided with a transverse passage 44, adapted to aline with the bore of the pipe 5 when 90 the tube 42 is in position within the branch 7 and through which the tube 37 is free to pass, the arrangement being shown in Fig. 6. The inner end of the tube 42 is split by means of the elongated opposite slots 45, whereby it 95 passes freely over the projecting end of the valve 10. When it is desired to clean the pipes 5 and 7, the tube 37 is first withdrawn, and the tube 42 may then be also withdrawn. The passage 40 of the tube 37 communicates 100 with the interior of the tube 42 when the parts are assembled.

Having described my invention, what I claim as new, and desire to secure by Letters Patent, is—

110

1. In a vapor-burner, the combination with a retort having a passage, of a reversible slidable cut-off for the passage, provided with a main and an auxiliary mixing-tube movable in alternation into alinement with the said passage and the latter of which tubes discharges upon the cut-off.

2. In a vapor-burner, the combination with a retort having a passage, of a reversible cut-off for the passage consisting of a sliding plate provided with a main and an auxiliary mixing-tube disposed on the line of movement of the plate.

3. In a vapor-burner, the combination with a retort having a passage, of a reversible cut-off for the passage consisting of a sliding plate having integral main and auxiliary mixing-tubes.

4. In a vapor-burner, the combination with a retort having a base-plate provided

125

130

- with a central passage, headed lugs on the base-plate, a sliding plate having elongated slots to receive the lugs, a pipe having a valved exit alined with the passage, and a 5 pair of mixing-tubes carried by the plate and adapted to be placed in alinement with the oil-exit at will, one of said mixing-tubes opening onto the plate and the other into the passage when the plate is moved to place the 10 latter tube in alinement with the oil-exit.
5. In a vapor - burner, the combination with a retort having a passage, and guides on the retort, of a sliding cut-off mounted on the guides, a main mixing-tube on the cut-off adapted to register with the passage when the 15 cut-off uncovers the same, and an auxiliary mixing-tube on the cut-off in the line of movement of the main mixing-tube to discharge upon the portion of the cut-off that 20 closes the passage.
6. In a vapor - burner, the combination with a retort having a central passage, and headed screws on the base of the retort, of a plate provided with slots to receive the screws, 25 a main mixing-tube on the plate and adapted to register with the passage when the plate uncovers the passage, an auxiliary mixing-tube on the plate and opening upon the same, and a rib on the plate.
- 30 7. A cut-off for vapor-burners comprising a sliding plate having a downwardly-deflected central portion, a main tube passing through the central portion, and an auxiliary tube opening upon the under side of the plate.
- 35 8. In a vapor - burner, the combination with an annular retort having downward projections, of a deflecting - plate secured thereto and having upwardly-directed deflectors with intermediate passages at the 40 projections.
9. In a vapor - burner, the combination with an annular retort, of an inverted dish-shaped body overhanging the edge of the retort and provided with peripheral openings, and downwardly-directed supports for the 45 body resting on the retort, an oil - supply connection leading to the retort, and a vapor connection leading from the retort and having an orifice directed toward the bottom of 50 the dish-shaped body.
10. A vapor-burner having a gas-passage consisting of angularly-disposed branches of different diameters, a hollow cleaning-tube in the larger branch having a transverse passage, and a hollow cleaning-tube in the smaller branch within the said transverse passage of the larger tube and having a lateral exit in register with the said first cleaning-tube. 55
11. A vapor-burner having a gas-passage 60 consisting of cross branches of different diameters, the inner end of the larger branch having a gas-exit, a cap closing the outer end of each branch, a hollow cleaning-tube in the larger branch and having a hole to receive a 65 removing-tool when its associated cap is removed, said tube provided with a transverse passage in register with the smaller branch, a second hollow cleaning-tube in the smaller branch having a hole to receive a removing- 70 tool when its associated cap is removed, said second tube passing through the passage in said first tube and having an exit in register with said first tube.
12. A vapor-burner having a gas-passage 75 consisting of cross branches of different diameters, one end of one of said branches having a gas-exit, a needle-valve for said gas-exit, a hollow cleaning-tube removably mounted in each branch, one of said tubes passing 80 through the other, and the tube in the exit branch being split to straddle the valve.
13. In a vapor - burner, the combination with a retort having a mixing-passage, of a cut-off mounted on the retort and provided 85 with a mixing-tube rigidly mounted thereon normally in alinement with the mixing-passage and the upper end of which is spaced from the bottom of said mixing-passage so as to provide an air-inlet thereat. 90
